UNITED STATES PATENT OFFICE.

CHARLES E. HITCHINGS, OF NEW YORK, N. Y.

TRANSOM-LIFTER.

SPECIFICATION forming part of Letters Patent No. 340,716, dated April 27, 1886.

Application filed March 3, 1886. Serial No. 193,774. (No model.)

To all whom it may concern:

Be it known that I, CHARLES E. HITCHINGS, of the city and county of New York, in the State of New York, have invented a new and useful Improvement in Apparatus for Operating Pivoted Sashes, of which the following is a specification.

My invention is more particularly intended for operating the pivoted sashes which are employed in the roofs and sides of greenhouses, but may be also embodied in apparatus or sash-workers for operating any other pivoted sashes which are not readily accessible. Greenhouse sashes are commonly operated through arms carried by a rock-shaft, and with this rock-shaft is connected, by suitable gearing, an operating-shaft extending to a readily-accessible point. This gearing employed to connect the two shafts may advantageously consist of a gear-segment on the rock-shaft and a worm or screw carried by the operating-shaft. When apparatus of the same pattern is employed for operating either the roof-sashes or the side sashes of a greenhouse, the worm and operating-shaft must stand at different angles relatively to the rock-shaft carrying arms which are connected with the sashes, and it is often desirable to arrange the gearing and operating-shaft at different distances from a rafter or beam or post to which is attached a hanger whereby the apparatus is supported.

The object of my invention is to provide a simple means whereby the operating-shaft and worm or screw may be adjusted at different angles relatively to the rock-shaft and its arms, and whereby the gear-segment and worm and operating-shaft may be arranged at any desired distance from a rafter, beam, or post to which the apparatus is attached. In apparatus of this class the hanger, which is attached to a rafter, beam, or post, has commonly had attached directly to it, or formed directly with it, an arm which carries the bearing for the operating-shaft, and according to my invention I provide a long sleeve or tube, within which the rock-shaft is journaled, and which is provided with an arm carrying a bearing for the operating-shaft, and I secure this sleeve in the hanger by means of a set-screw or otherwise, so that it may be conven-

iently turned therein or adjusted axially in the hanger, as may be desired.

In the accompanying drawings, Figure 1 represents a sectional view of a portion of the roof of a greenhouse, including an elevation of my improved sash-operating device. Fig. 2 is a sectional view of a portion of the apparatus in a plane parallel with the rock-shaft carrying the arms which are connected with the sash, and upon a larger scale than Fig. 1; and Figs. 3 and 4 are respectively a side view and a plan of portions of the apparatus upon the same scale as Fig. 2.

Similar letters of reference designate corresponding parts in all the figures.

A designates a sash, pivoted at its upper edge, *a*, and which is moved to open and close it by means of rods *b*, extending from arms *b'*, and attached to its lower edge. The arms *b'* are carried by a rock-shaft, *B*, and this rock-shaft may be turned through suitable gearing connecting it with the operating-shaft *C*, which is here represented as vertical. The gearing here shown consists of a gear or worm segment, *B'*, on the rock-shaft *B*, and a worm or screw, *C'*, on the operating-shaft *C*.

D designates a long sleeve or tube, within which the rock-shaft *B* has a bearing, and which is itself supported by a hanger, *E*, adapted to be secured to a rafter, *A'*, or other beam or post. The sleeve or tube *D* is provided at its outer end with an arm, *D'*, carrying a bearing, *d*, for the operating-shaft *C*. As here represented, the extremity of the arm *D'* is forked, thereby forming two bearings, *d*, for the operating-shaft *C* and a space for the worm *C'* between them.

The sleeve or tube *D* is adjustably secured by a set-screw, *e*, in the hanger *E*, and when this screw is loosened the sleeve or tube *D* may be turned in the hanger *E*, or may be slid axially therein, and by either of such movements the position of the arm *D'*, carrying the bearing for the operating-shaft *C*, will be correspondingly changed. As here represented, the rock-shaft *B* is held in proper position lengthwise of the sleeve or tube *D* by a collar, *b*, on the shaft bearing against one end of the sleeve or tube, and the gear-segment *B'* bearing against the other end thereof.

From the above description it will be read-

ily understood that by turning the sleeve D the position of the arm D' will be changed so as to hold the operating-shaft C at any desired angle relatively to the rock-shaft, and by sliding 5 the sleeve or tube D axially in the hanger E the arm D' is adjusted to different positions more or less distant from a rafter or beam to which is secured the hanger E.

As here represented, the lower end of the shaft C is supported in a bearing, e, and said shaft may be operated by a crank or handle, C', applied to its lower end.

What I claim as my invention, and desire to secure by Letters Patent, is—

In a pivoted sash-worker, the combination, 15 with a rock-shaft carrying arms to be connected with the sash, an operating-shaft, and gearing connecting the two shafts, of a sleeve forming a bearing for the rock-shaft, and having a projecting arm carrying the bearing for 20 the operating-shaft, and a hanger wherein said sleeve is supported, and in which it may be turned and adjusted axially, substantially as herein described.

CHARLES E. HITCHINGS.
